[57] CLAIM

The ornamental design for a computer enclosure, as shown and described.

DESCRIPTION

FIG. 1 is a front, top, right side perspective view of a computer enclosure, showing our new design;

FIG. 2 is a rear, top, left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The Apple logo is shown in broken lines in FIGS. 1, 2, 5, and 6 for illustrative purposes only and forms no part of the claimed design.
